(57) **CLAIM**

The ornamental design for a motor vehicle, toy replica, and/or other replica as shown and described.

DESCRIPTION

This application contains subject matter related to the following co-pending U.S. design patent applications:

Application Ser. No. 29/851,212, filed Aug. 26, 2022 and entitled "Motor Vehicle, Toy Replica, and/or Other Replica";

Application Ser. No. 29/919,503, Filed Herewith and Entitled "Motor Vehicle, Toy Replica, and/or Other Replica";

Application Ser. No. 29/919,507, filed Herewith and Entitled "Motor Vehicle, Toy Replica, and/or Other Replica";

Application Ser. No. 29/919,508, filed herewith and entitled "Hood for a Vehicle";

Application Ser. No. 29/919,510, filed herewith and entitled "Front Bumper for a Vehicle";

Application Ser. No. 29/919,513, filed herewith and entitled "Front Fender for a Vehicle";

Application Ser. No. 29/919,514, filed herewith and entitled "Rear Bumper for a Vehicle";

Application Ser. No. 29/919,519, filed herewith and entitled "Headlight for a Vehicle"; and

Application Ser. No. 29/919,522, filed herewith and entitled "Taillight for a Vehicle".

FIG. 1 is a left, front perspective view of a motor vehicle, toy replica, and/or other replica according to the design;

FIG. 2 is a left side view thereof;

FIG. 3 is a right side view thereof;

FIG. 4 is a right, rear perspective view thereof;

FIG. 5 is a front view thereof;

FIG. 6 is rear view thereof; and,

FIG. 7 is a top view thereof.

1 Claim, 7 Drawing Sheets
